UNITED STATES PATENT OFFICE.

CHARLES SPIELMAN, OF NEW YORK, N. Y., ASSIGNOR TO WM. A. FORCE & COMPANY, INC., OF NEW YORK, N. Y., A CORPORATION OF NEW YORK.

NUMBERING MACHINE.

Application filed March 3, 1925. Serial No. 12,868.

To all whom it may concern:

Be it known that I, CHARLES SPIELMAN, a citizen of the United States, residing at Queens Borough, New York city, in the county of Queens and State of New York, have invented certain new and useful Improvements in Numbering Machines, of which the following is a specification.

My invention relates to improvements in hand stamps, such as dater and numbering machines, and it is my object to simplify and cheapen the construction of such stamps so that they may be more quickly and easily assembled and alined, to provide a simplified form of stop catch to hold the printing head down in the main frame while inking the pad or setting the type wheels, to provide the printing head with unitary, combined ratchet pawls and springs which may be independently adjusted to aline the symbols on the type wheels, and finally to provide the ink pad carrier links with extensions to increase their bearing surfaces on the main and sub-frames to prevent cramping and twisting although they are loosely mounted on their pivots instead of being riveted or screwed in position.

In the drawing Fig. 1 is a sectional view of my improved hand stamp; a dater being selected for purposes of illustration; Fig. 2 a rear view of the lower part of the structure of Fig. 1; Fig. 3 a front view of the lower part of the structure of Fig. 1; Fig. 4 a side view of the lower part of the structure of Fig. 1, partly in section; Fig. 5 a sectional view of the lower part of the structure of Fig. 1, on the line 5—5 thereof; and Fig. 6 a detail view of the combined spring and pawl.

The stamp consists of the usual main frame composed of sides 1 and 2 connected by a top plate 3, in which main frame the printing head composed of a sub-frame 5 carrying printing wheels 6 is mounted. This printing head is reciprocated in the main frame by a stem 7 secured to the sub-frame 5 and passing through the top 3 of the main frame. To normally hold the printing head up a spring 8 is coiled around the stem 7 and bears against the flanged bottom of a sleeve 9 surrounding it at one end, the other end of the spring bearing against an abutment washer 10 secured to the upper part of the stem. A knob 11

on the upper end of the stem affords a hand grip.

To lock the printing wheel head in the downward position while inking the pad or setting the wheels a washer 12 provided with a domed top and a lip or hook 13 is placed between the lower end of the sleeve 9 and the top of the main frame with the hook engaging the edge of the top plate. This forming of the washer gives a finished base effect to the sleeve 9. The stem 7 is grooved at 14 so that when the stem is pushed down the washer 12, through which it passes, may be pushed into the notch to lock the printing head in downward position. This washer 12 is held in position by the pressure of the spring on the sleeve which holds the washer slidably between the end of the sleeve and the top of the main frame. A projection 26 on the inside of the washer engages a groove 27 in the top of the main frame and prevents any twisting movement of the washer. In this way the lock is held in place without the use of any special securing means and the bolts and pivoted washers or levers heretofore used for this purpose are eliminated.

Heretofore it has generally been customary to hold the printing wheels in alignment by pawls pivoted to the sub-frame and engaging ratchet wheels secured to the type wheels, the pawls being forced into engagement by a plurality of springs struck up from a single piece of metal and bearing against the pawls. I employ a separate spring 14 for each printing wheel and secure the pawl 15 directly on it. The upper part of each spring has an elongated screw hole 16 and is secured to the sub-frame 5 by a screw 17, as shown in Fig. 3. Each pawl 15 engages a ratchet wheel 18 secured to a type wheel. To aline the printing symbols on the type wheels in proper printing position the springs are slid up or down on the sub-frame to turn the wheels on their axes, while a pawl engages a ratchet wheel, until the symbols on the wheels are exactly alined in printing position, after which the screws are driven home. In this way slight variations in the type wheels and their attached ratchet wheels may be compensated for.

To further afford quick and easy assembly of the machine the ink pad carrier 19

is pivoted to the main frame on a pin 20, one end of which screws into one side of the main frame. The ears of the ink pad carrier have a pin 21 passing through them which pin is long enough to extend between the inner walls of the sides of the main frame. Each side of the sub-frame 5 has a stud 22 thereon and a pair of links 23—24 are pivoted on the ends of the pin 21 and on the studs 22 so that as the printing head reciprocates the ink pad carrier will swing out on the down stroke and against the type wheels on the up stroke.

The loose pin 21 is always inside the boundaries of the main frame so that no mechanical fastening is required to hold it in position. The links lie in the spaces between the main frame and the sub-frame carrying the printing wheels and are held on their pivots without riveting or screws. The links extend outwardly at the top and inwardly at the bottom as best shown in Figs. 1 and 4, to afford increased bearing surfaces against the outer face of the sub-frame and the inner face of the main frame to prevent cramping or twisting which might otherwise occur due to the fact that the links are not screwed or riveted in position. The notches in the opposite edges of the links are necessary to clear the pin 20 and the axis on which the type wheels revolve.

Openings 25 may be made in the bottom edges of the sides of the main frame to indicate the printing point.

35 I claim:—

1. A numbering machine comprising a main frame having sides and a top, a circumferentially grooved stem passing through said top, a printing head secured to one end of the stem and adapted to reciprocate between the side walls of the main frame, a washer on the stem bearing directly against the outside of the frame top and adapted to engage the stem groove, a sleeve surrounding the lower part of the stem and bearing on the washer, a spring surrounding the stem and within the sleeve with one end bearing on the sleeve and an abutment on the upper portion of the stem against which the other end of the spring presses whereby the washer is held in slidble position to engage the stem groove to lock the printing head in downward position.

2. A numbering machine comprising a main frame having sides and a top, a grooved stem passing through said top, a printing head secured to one end of the stem and adapted to reciprocate between the side walls of the frame, a washer on the stem bearing directly against the outside of the frame top and adapted to engage the stem groove, a hooked lip on said washer extending over the edge of the frame top

to position the same, a sleeve surrounding the lower part of the stem and bearing on the washer, a spring surrounding the stem and within the sleeve and an abutment on the upper portion of the stem against which the other end of the spring presses whereby the washer is slidably held in position to engage the stem groove to lock the printing head in downward position.

3. A numbering machine comprising a main frame, a stem therein, a printing head on said stem adapted to reciprocate within the frame, said printing head comprising a plurality of type wheels and attached ratchet wheels, flat springs secured at one end to said printing head, a pawl rigidly secured to the other end of each of said springs in position to engage a ratchet wheel, said springs being provided with elongated slots through which the securing means extend whereby the pawls may be positioned to hold the type wheels in alinement.

4. A numbering machine comprising a main frame, a stem therein, a printing head on the stem adapted to reciprocate in the frame, ink pad mechanism comprising an ink pad holder, a pivot pin secured to the frame and on which the ink pad holder swings, links having outwardly projecting upper portions and inwardly projecting lower portions on either side of said holder and between it and the frame, a second pin loosely held in the ink pad frame and within the line of the frame on which the lower ends of the links are loosely pivoted and studs on the printing head to which the other ends of the links are loosely pivoted, the link extensions affording increased bearing surface and preventing cramping and binding.

5. A numbering machine comprising a main frame having sides and a grooved top, a circumferentially grooved stem passing through said top, a printing head secured to one end of the stem and adapted to reciprocate between the side walls of the main frame, a washer, a projection thereon, said washer encircling the stem with the projection in the groove in the frame top and bearing on the latter, said washer being adapted to engage the stem groove, a sleeve surrounding the lower part of the stem, a spring on the stem within the sleeve with one end bearing thereon, and an abutment on the upper part of the stem against which the other end of the spring presses, whereby the washer is in slidble position to engage the stem groove to lock the printing head in downward position.

In testimony whereof I have affixed my signature.

CHARLES SPIELMAN.
